UNITED STATES PATENT OFFICE.

HENRY CONRAD HEBIG, OF NEW YORK, N. Y., ASSIGNOR, BY MESNE ASSIGNMENTS, TO
CHARLES D. SIMONS, JR., AND HENRY VON L. MEYER, BOTH OF NEW YORK, N. Y.

TOBACCO-STEMMING MACHINE.

1,073,853.

Specification of Letters Patent. Patented Sept. 23, 1913.

Application filed April 5, 1913. Serial No. 759,071.

To all whom it may concern:

Be it known that I, HENRY CONRAD HEBIG, a citizen of the United States, residing at New York city, in the county of New York and State of New York, have invented certain new and useful Improvements in Tobacco-Steaming Machines, of which the following is a specification, reference being had therein to the accompanying drawing.

10 This invention relates to a tobacco-stemming or stripping machine.

In the accompanying drawings illustrating the best form now known to me of embodying the features of my invention, Figure 1 is an elevation of one side; and Fig. 2 is an elevation of the other side of the machine. Fig. 3 is a top plan view thereof. Fig. 4 is an elevational view, partly in transverse section at line 4-4 of Fig. 3, looking at the discharge or ejection side of the stripping rolls. Fig. 5 is a view partially in vertical section at line 5-5 of Fig. 3, and partly in elevation and mainly shows the auxiliary stem-gripping mechanism at the rear side 25 of the stripping rolls which are shown in transverse section. A portion of a wiper mechanism is also shown at the discharge side of the rolls. Fig. 6 is an elevational view, partly in section, at line 6-6 of Fig. 3; and shows mainly the main and auxiliary stem-gripping devices and some of their respective actuating and controlling mechanisms. Fig. 7 is an enlarged detail view, partly in section, at line 7-7 of Fig. 3, and shows a portion of the continuous slip-belt drive for the under stripping-roll, the main stem-grips between the under and upper stripping-rolls; means for separating the rolls, means for cushioning the approach of the rolls, and a portion of a mechanism for accelerating the rotational speed of the under roll by which quick ejection and stem-snapping movements are accomplished. Fig. 8 is a detail view, partly in elevation and partly in section, at line 8-8 of Fig. 7, of the clutch devices which form a portion of the speed-accelerating mechanism. Fig. 9 is a side elevational view, partly in section at line 9-9 of Fig. 7, of the stripping-roll-separating devices. Fig. 10 is an enlarged elevational view of intermeshing gear mechanism for accelerating the rotational speed of the under stripping-roll, and Fig. 11 is a top plan view of what

is shown in Fig. 10. Fig. 12 is a cross-sectional view of the main and auxiliary stem-grips to show corrugations on their operative surfaces, such corrugations being omitted from the other views. Fig. 13 is a sectional view showing both stripping rolls 60 covered with wire card-clothing, the teeth being bent and all pointing in the direction of the feed-in end of the machine at their operating line of contact with the upper and under sides of the leaf.

65 Referring to the drawings, the specific construction and mode of operation of the machine are as follows:

Main stem gripping and pulling mechanism.—Frame A at its front end has a table 70 T from which a number of unstemmed tobacco-leaves are fed, the butt ends of the stems being gripped by transverse upper and lower jaw-bars referred to hereinafter as the main grips. The front end of the 75 frame supports the transverse shafts a and a' , one above the other, and the rear end of the frame supports the transverse shafts a^2 and a^3 , one above the other. Shaft a carries a pair of sprocket wheels 1 spaced laterally apart; shaft a' carries a pair of sprocket-wheels 2 each in line with a sprocket-wheel 1; shaft a^2 carries a pair of sprocket-wheels 3 each in line with a sprocket-wheel 1; and shaft a^3 carries a pair of sprocket-wheels 4 each in line with a sprocket-wheel 3 and with a sprocket-wheel 2. At each side of the machine, the upper sprocket-wheels 1 and 3 are connected lengthwise of the machine by an endless upper sprocket-chain 90 85 5, and at each side of the machine, the under sprocket-wheels 2 and 4 are connected by an endless under sprocket-chain 6.

Frame A carries a transverse driving shaft a' provided with a main driving-pinion 95 7 (Fig. 2) and carrying driving pulley P. Pinion 7 meshes with and rotates gear 8 on shaft a^3 , and gear 8 meshes with and drives gear 9 on shaft a^2 . Hence the upper pair of sprocket-chains 5 and the under pair 100 of sprocket-chains 6 are driven simultaneously and at the same speed when power is transmitted to pulley P. The direction of the movement of the sprocket-chains, as indicated by arrows (Fig. 2) is such that the 105 adjacent runs of the chains 5, 5 and 6, 6 travel away from the front or feed end of the machine. The upper chains 5, 5 carry

one or more transverse, upper, main stem-grips α and the under chains 6, 6 carry a corresponding number of transverse, under main stem-grips γ (Figs. 8, 5 and 7). These 5 grips coöperate in pairs and are brought into stem-gripping position as they are carried by their supporting chains around the front peripheries of the front end sprocket-wheels 1, 1 and 2, 2. The adjacent runs of 10 the chains, carrying the main stem-grips in butt-gripping position travel through longitudinally-extending guideways a^* , a^* which are spaced laterally apart and supported each on a suitable bracket a^* (Figs. 8, 6 and 15 7) of frame A. The ends of the main stem-grips are secured to the chains and the guideways a^* keep the grips in stem-gripping position while the grips are traveling rearwardly away from the feed-table.

20 *Continuous driving mechanism for stripping-rolls, and stripping-roll construction.*—Shaft a has a pulley 10 (Figs. 2 and 3) from which a belt 11 runs to a pulley 12 on a stud 13 which also has a pulley 14 from 25 which a cross-belt 14 runs to a pulley 15 on shaft 16 of the under, transverse stripping-roll 17 (see Fig. 7) which is surfaced with wire teeth card-clothing, the free ends of the teeth being bent to point, when in 30 contact with the tobacco leaf, in the direction of the feed end of the machine (Fig. 5). By means of such shafts, pulleys and bolts, under roll 17 is rotated continuously during the stemming and stripping operation. Roll 17 is journaled at each end in vertically-movable boxes 18 located in openings a' of frame A. These boxes are supported on springs 19 the tension of which is adjustable by means of screw devices 20. 40 The upper stripping-roll 21 is preferably surfaced with a rubber cylinder which is preferably slightly corrugated annularly as shown. This upper roll is carried by a transverse shaft 22, the opposite end portions of which are each provided with a cam 23 having a high point 24 (Figs. 8, 7 and 9). Each cam 23 coöperates with a disk 25 on the under-roll shaft 16 in separating the stripping rolls for travel between them 50 of the main grips clamped on a stem butt or butts.

At each end, the upper-roll shaft 22 is journaled in a box 26 located in an opening a' in frame A, a spring 27 being located in 55 each opening above a box and provided with a tension-regulating screw-device 28. Rolls 17 and 21 are separated, for travel between them of a pair or successive pairs of the main grips when they are carrying a stem 60 butt or butts, by engagement of the high points 24 of cams 23 with disks 25. This separating movement is against the tension of springs 19 and 27 which press the rolls one toward another upon the leaf blade after 65 a pair of main grips have traveled between

the rolls and while the main grips are traveling from the rolls toward the rear of the machine. During this interval the main grips are pulling on the stem or stems and the operating surfaces of the rolls are slowly rotating continuously in the opposite direction, that is toward the table. 70

Contact of the two portions of cams 23 with disks 25 limit the inward approach of the stripping rolls, but it is very important 75 that this approach which involves the nipping of the tobacco leaf by said rolls should be gentle for otherwise the leaf blade is apt to be pierced by the wire teeth of the under roll and ragged in the stripping operation. 80 To secure this gentle approach and to make it gradual, the end portions of upper stripper-roll shaft 22 are also each provided with a disk 29 having a rubber or cushioning periphery 30 which has a normal diameter somewhat greater than that of the adjacent cam 23 which is a disk having a high point 24; and each end portion of the under stripper-roll shaft 16 is provided with a disk 31 having a rubber or cushioning periphery 32 which has a normal diameter greater than that of the adjacent disk 25. The cushioning disks 29 and 31 coöperate in pairs at each end of the stripping rolls and as, in the roll approaching 85 movement under the tension of springs 19 and 27, they contact compressively and slightly before the disks 25 contact with cams 23, the compression of the leaf blade between the rubber surface of the upper, and the wire-toothed surface of the under, stripping-roll is very gentle and is effected without undue liability of injuring the leaf blade. Upper roll 21 is rotated at the same speed as and continuously with under roll 17, as described below, by positive means; but the frictional contact of the disk surfaces 30 and 32 would effect the proper continuous rotation with some grades of tobacco even if the positive drive for the 90 upper roll were omitted. 100

105 *Acceleration of the stripping-roll speed during a part of each rotation for quick ejection and snapping of stems.*—At one side of the machine, under-roll shaft 16 has a disk 33 (Fig. 7) keyed to it at 34 and provided on its inner face with a lug 35 which travels in the path of a lug 36 carried by a loose gear 37 on the same shaft. As arranged in the present form of machine, 110 lug 36 engages lug 35 when the rolls have completed about two-thirds of a complete rotation, the lugs remaining in such engagement during the remaining one-third of the complete rotation; and during this 115 period of engagement the continuously-rotating stripping rolls have their speed accelerated for the two-fold purpose of bringing a strain or snapping action on the leaf stem about one-third of the way from its 120 125 130

tip to its butt end, and to quickly move away from the rolls the accumulating blade-leaf as it is stripped from the greater part of the stem by the stem-pulling movements of the main grips and the oppositely effective stripping movements of the rolls. In practice, on the grade and average size of tobacco for which the present machine is more particularly intended, it is generally desired to leave the tip end portion of the stem, for about one-third of the length of the stem between the blades, intact with the blade, as this tip end portion is commercially usable and valuable.

16 The present construction has grip-chains of sufficient length to carry three pairs of main grips at equal distances apart, and the circumferential movement of the stripping rolls is such as to correspond approximately 20 to the length of the blade to be stripped away from about two-thirds of the length of the stem, measuring from the butt toward the stem.

The accelerating drive for the under roll (Figs. 7, 10, 11 and 1) is at the side of the machine opposite the continuous belt-drive above described, and comprises said loose gear 37 which meshes with gear 38 on stud 30 journaled in frame A, gear 38 meshing with gear 40 on stud 41 which also has a gear 42 that is mutilated at 43 when it is opposed to the mutilated portion 44 of gear 45 on the transverse shaft 46 which is journaled on the side frames of the machine. This shaft 46 has a sprocket-wheel 47 from which sprocket-chain 48 runs (Figs. 1 and 3) in engagement with idler 49 over sprocket-wheel 50 on the shaft a^* , rotation of which effects simultaneous travel of the 40 main grips and rotation of the mutilated gear 45 by means of the described instrumentalities.

Shaft 46 and shaft a^* rotate at the same speed; and when mutilated portion 44 of 45 gear 45 is opposed to mutilated portion 48 of gear 42, no movement is communicated to the gears 40, 38 and 37. At each interval, the under stripper-roll is rotating continuously at uniform speed. But when the gear 45 meshes with gear 42, then, through the intermediate gears, gear 37 is rotated quickly, causing lug 36 to catch up with lug 35 by contact of which with lug 36, the under stripper-roll shaft and roll are given 50 an accelerated movement during the time that gear 45 meshes with gear 42; and while gear 45 is in mesh with gear 42, the continuously-driving pulley 15 slips on belt 14 so that the latter does not arrest the quick 60 accelerating movement of the understripping-roll. When the acceleration movement is completed, the mutilated portions 44 and 48 become again opposed, stopping rotation of gears 42, 40, 38 and 39, and at 65 this interval of such inactivity, the continu-

ous rotation of disk 33 carrying the lug 35 carries the latter out of contact with lug 36. Both stripping rolls are rotated very slowly except during the acceleration movement. The stem-grips travel at a relatively higher speed than the stripping rolls.

The upper stripping-roll drive.—At each end portion of the upper-roll shaft 22 it is provided (Figs. 7 and 8) with a sprocket-wheel 60 from which a sprocket-chain 61 runs over a sprocket-wheel 62 on the shaft 46, which shaft is continuously rotated from shaft a^* by means above described. To prevent reversal of the rotational direction of the upper roll in consequence of the pull of the stem toward the rear end of the machine, in case the positive drive of the upper roll should fail in consequence of undue wear of the parts or the like, the upper-roll shaft is provided with a ratchet-wheel 63 provided with a pawl 64 (Fig. 3), this ratchet wheel and pawl being a precautionary device.

The stripping-roll wiper mechanism.—Heretofore in this class of machines great difficulty has been met in getting the stripped leaf blade away from the stripping rolls without injury to the leaf blade. In the present machine the desired result is accomplished, by means of a wiper that clears the rolls (or more particularly the lower roll) throughout their length, and also the comb 79, the wiper 70 extending transversely of the machine and being connected at each end to a sprocket-chain 71. There are two sprocket wheels 72, one journaled on one side frame and the other journaled on the other side frame of the machine. Below each sprocket wheel 72 there is a sprocket wheel 73 journaled on a side frame of the machine. Nearer the front end of the machine, its side frames are each provided with a thereon-journaled sprocket wheel 74, and each chain 71 runs over three sprocket wheels 72, 73 and 74. As the sprocket wheels 72 and 73 are mounted one above the other at each side of the machine, the transverse wiper 70 is moved during its wiping operation when adjacent to the stripping rolls, in an approximately vertical path, and this movement is downwardly and perpendicularly to the plane of the horizontal travel of the leaf and stems. Each sprocket wheel 74 is mounted on the transverse shaft 75, which has a sprocket-wheel 76 from which a sprocket-chain 77 extends around a sprocket-wheel 78 on shaft a^* (Figs. 2 and 3). The wiper is shown as a brush and it is timed in its movement so as to bring it successively into wiping relation with the leaf blade present at the ejection side of the stripping rolls, and into contact with the stationary, transverse comb 79 preferably provided for the under stripper-roll (Figs. 4 and 8). This transverse wiper serves efficiently to clear the rolls and comb of the

stripped blade and to strike the stripped leaf downwardly free of the receiving comb as herein described, without injury to the leaf.

The transverse wiper during a portion of its travel comes into the path of the main stem-grips from the feed-table to the stripping-rolls, and consequently must be moved out of such path when the wiping or clearance is effected in order that the next succeeding pair of main stem-grips may travel along that path. The sprocket-wheels 72 and 74 are accordingly located in a plane above the sprocket-wheels 73, the sprocket-wheels 72 and 73 being located one above the other, as above noted, adjacently to the stripping rolls. Consequently in its wiping movements, the wiper 70 travels downwardly out of said path and, while main stem-grips are traveling from the feed end of their path to the stripping rolls, the wiper is traveling toward the feed end of the machine below the path of the main stem-grips; and, after turning about shaft 75 which is below said path, it follows said

grips and operates on the leaf blade stripped by the rolls from the stems held by such grips. This wiping mechanism may be called a main stem-grip dodging, wiping-mechanism.

20 The conveyer belts and separating mechanism.—The stripped leaf is wiped downwardly and falls on an endless conveyer-belt 80 which extends transversely of the machine. Between this belt and the feed end of the machine a similar belt 81 is located, but the upper runs of the belts travel in opposite directions. Frame A is provided with a vertical partition 82 (Figs. 1 and 3), which rises from near the opposed edges of these belts, and a transversely-extending roller 83 is journaled in the sides of frame A with its upper side just under the horizontal path of the main stem-grips. Roller 83 is rotated by means of a gear 84 on its shaft and a gear 85 fixed on a journal 85 of the sprocket wheels 72. The upper surface of the roller travels toward the feed end of the machine. Consequently roller 83 affords a support over which the leaf drags as it is being carried by the main stem-grips from the feed-table to the stripping-rolls, and if a stem breaks in such travel of the leaf, the roller tends to feed the leaf released from the main stem-grips backwardly in the direction of the feed-table and to discharge such unstemmed leaf on belt 81. The partition 82 prevents the unstemmed leaves discharged on belt 81 from being mixed with the stemmed product falling on belt 80, and the unstemmed leaf and stemmed leaf are conveyed to opposite sides of the machine. At one side of the machine, a horizontally-extending shaft 87 carries a pair of rolls 88 over one of which belt 80, and over the other of which belt 81, extends.

At the opposite side of the machine, belt 80 runs over a roll on shaft 89 provided with a gear 90 which meshes with a gear 91 on a horizontal shaft 92, an end of which has a bevel gear 93 in mesh with a bevel gear 94 on shaft a' (Figs. 2 and 3). Thus belt 80 is driven in one direction. To drive belt 81 in the opposite direction, its shaft 95 is provided with a sprocket-wheel 96 from which a sprocket-chain 97 runs over a sprocket-wheel 98 on shaft 92.

The auxiliary stem-grip mechanism.—As it occasionally happens that a stem will break off at an undesired point between the stripping-rolls and the stem-discharging end of the machine (and at a point in the stem short of the usually desired break which is ordinarily about one-third of the stem length from its tip) auxiliary stem-gripping mechanism which, like the wiping mechanism, must dodge the main stem-grips, is located between the stripping rolls and the rear end of the machine, adjacently to the rolls. This auxiliary mechanism comprises a transverse upper stem-gripping bar 100 and a transverse under stem-gripping bar 101 which first grip the stem after the main stem-grips have pulled the stem a sufficient distance rearwardly of the rolls. The ends of bar 100 are secured to side sprocket-chains 102, and the ends of bar 101 are secured to similar chains 103 (Figs. 5, 6, 2 and 3). Each chain 102 runs over sprocket-wheels 104, and each chain 103 runs over sprocket-wheels 105. The four upper sprocket-wheels 104, two at each side of the machine, are carried by transverse shafts 106 and 107. The four under sprocket-wheels 105 are carried, two at each side of the machine, by transverse shafts 108 and 109.

To compel the grip-bars 100 and 101 to travel in proper working relation for seizing and releasing the stem, shaft 107 has a gear 110 which meshes with a gear 111 on shaft 109. Shaft 107 has a driving sprocket 112 from which a sprocket-chain 113 runs over a sprocket-wheel 114 on shaft a' (Fig. 3). The adjacent runs of upper chains 102 and of under chains 103 carry the auxiliary grip-bars 100 and 101 in the path of the main stem-grips 7 and 8 (see Figs. 5 and 6), and the upper sprockets 104 and lower sprockets 105 are held spaced properly apart in the vertical direction by the brackets 115 in which the shafts 107 and 109 are journaled, the ends of the auxiliary grip-bars being bent at 116 (Fig. 6) for such connection with sprocket-chains 102 and 103 as suffices to hold their transverse portions in the path of the main grip-bars 7 and 8. In their travel, following up the main stem-grips, the auxiliary grip-bars release the stem as chains 102 and 103 travel around shafts 107 and 109, while the main stem-grips continue to travel in the rear

of the machine as described above; and while the auxiliary grips are traveling toward the stripping-rolls they are moved in that direction by the outermost runs of 5 chains 102 and 103, and first nip the stem just after the main stem-grips have moved sufficiently rearwardly of the rolls. Such positions of the main and auxiliary grips are shown in Fig. 5.

- 10 To insure a tight grip of the auxiliary grip-bars on stems and to prevent the bars from springing or becoming sprung apart, parallel, lengthwise-extending shoes 117 are located midway between the sides of frame 15 A, one below the other and forming a guideway for the auxiliary grip-bars 100 and 101, each of the latter, as shown, having a lengthwise-extending boss 118 which contacts with the adjacent shoe. The shoes are held in 20 place by transverse bars 119 secured to the guideway members a^* from which the comb is suspended as shown in Fig. 4.

Cleaners for main stem-grips.—These grips become frequently gummed with stem 25 juices and are cleaned by passing, at the rear end of the machine, against transverse brushes 120 held in place by bars 121 attached at their ends to frame A.

The various groups of mechanisms above 30 described may be changed in mechanical details without departure from this invention, and for some grades and sizes of tobacco leaf it may be preferred to clothe the upper stripping-roll with wire toothed card-clothing 35 as is shown in Fig. 18 where both stripping rolls are so surfaced in a known manner. It is not to be understood that use of the rubber surfaced rolls 29 and 81 is absolutely essential to the gentle gripping approach of the stripping rolls, because the 40 construction of rolls 25 and cams 28 may be such as to effect the desired result in this connection. The flanged ends of the gripping bars (Fig. 12) are perforated at x^* , 45 y^* for connection with the chains which carry the bars, and the bars are preferably lengthwise serrated as shown. The transverse wiper for the stripping rolls must be timed to dodge the main stem-grips also extending transversely of the machine, and the transverse auxiliary-stem-grips must 50 also be timed to dodge the main stem-grips. The wiper and auxiliary stem-grips are accordingly designated respectively as a main-stem-grips-dodging wiper, and as main-stem-grips dodging auxiliary-stem-grips. The 55 latter may be omitted with some grades and sizes of tobacco. The interlocking-pin construction described in relation to the acceleration of the stripping rolls is one of many forms of clutch constructions whereby the positively driven stripping rolls may have their rotational speed accelerated during a 60 part of each complete rotation, the positive and continuous drive of the under roll not

being thereby arrested in consequence of the slip of belt 14 on the pulley 16 or the slip of the pulley 16 relatively to the belt 14. That is, belt 14 drives the under roll continuously and also positively during the greater part of its rotation, and the clutch action of the lugs 85 and 86 continues the positive and continuous rotation of the under roll during the accelerated portion of its rotation. The comb may be omitted in some cases.

70 While both stripping rolls are shown movable toward and away from the path of the main stem grips, such arrangement is a mere mechanical detail. One of the rolls may be journaled in stationary supports, if 75 preferred, and as shown in Cochrane's British Patent No. 1,188 of 1894 and United States Patent No. 538,660 of May 7, 1895, the present invention being a development 80 of the machine shown in the Cochrane patent. 85

What I claim is:

1. In a tobacco-leaf stemming-machine, the combination of a pair of separable stripping-devices; means for pulling a tobacco-leaf stem between and away from them; and a transverse, traveling wiper operatively adjacent to and parallel with the stripping devices. 90

2. In a tobacco-leaf stemming-machine, the combination of a pair of separable stripping-rolls; main stem-grips; means for moving the grips between and away from the rolls; and a traveling wiping mechanism comprising a transverse grip-dodging wiper. 100

3. In a tobacco-leaf stemming-machine, the combination of a pair of stripping-rolls with a transverse wiper mounted parallel with the rolls, and means for carrying the wiper into and through and, out of its working position, in a direction approximately perpendicular to the plane in which the rolls contact with a leaf. 105

4. In a tobacco-leaf stemming-machine, the combination of a pair of main stem-grips; means for moving them; and a pair of auxiliary stem-gripping bars operative in the path of the main stem-grips, and means for carrying the auxiliary stem-gripping bars into, along and out of the path of the 110 main stem-grips.

5. In a tobacco-leaf stemming-machine, the combination of a pair of separable stripping-rollers; a pair of main stem-grips; and means for carrying them to, between and 115 away from the stripping rolls of a pair of main stem-grips dodging auxiliary stem-grip bars located on the rear side of the stemming rolls.

6. In a tobacco-leaf stemming-machine, the combination of main stem-grips; means for moving them to, between and away from separable stripping rolls; means for rotating the working portions of the stripping rolls continuously and in a direction opposite to 120

130

the travel of the main stem-grips; and a transverse leaf-support between the discharge side of the stripping rolls and the feed-end of the machine, and operative to move a broken stem with its leaf away from the stripping rolls.

7. In a tobacco-leaf stemming-machine, the combination of a pair of separable stripping-rolls, main stem-grips, means for moving them to, between, and away from the stripping-rolls, a transverse conveyer-belt below the stripping-rolls, a transverse leaf-support between the discharge side of the stripping rolls and the feed-end of the machine, means for rotating the upper surface of said leaf-support in the direction of the feed-end of the machine, a transverse conveyer-belt located under said support, and means for rotating said conveyer-belts in opposite directions.

8. In a tobacco-leaf stemming-machine, the combination of a plurality of separable stemming-devices, main stem-grips, means for moving the main stem-grips to, between and away from the stemming-devices, a wiping mechanism comprising a transverse wiper movable into, through, and out of the path of said grips, auxiliary stem-grips, and means for moving them into, through and out of the path of the main stem-grips, the wiper being between the feed-end of the machine and the stripping-devices, and the auxiliary stem-grips being between the stemming-devices and the discharge-end of the machine.

9. In a tobacco-leaf stemming-machine, the combination of a plurality of separable stemming-devices, main stem-grips, means for moving the main stem-grips to, between and away from the stemming-devices, a wiping mechanism comprising a transverse wiper movable into, through, and out of the path of said grips, auxiliary stem-grips, and means for moving them into, through, and out of the path of the main stem-grips, the wiper being between the feed-end of the machine and the stripping-devices, and the auxiliary stem-grips being between the stemming-devices and the discharge-end of the machine, a conveyer-belt under the stripping-rolls, a transverse leaf-support between the stripping-rolls and the feed-end of the machine, a conveyer-belt under the leaf-support, and means for moving said conveyer-belts in opposite directions.

10. In a tobacco-leaf stemming-machine, the combination with upper and lower, transverse, main stem-grips; means for carrying them in an endless path; and in the path of each grip a transversely-extending brush against and past which a stem-grip is moved in its course.

11. In a tobacco-leaf stemming-machine, the combination of an upper stripping-roll and an under stripping roll, means for auto-

matically separating them, means for automatically approaching them, means for continuously rotating the under roll, means for continuously and positively rotating the upper roll, and means for accelerating the 70 rotational speed of the under roll during its continuous-rotation, said means comprising a slip-belt-drive and also comprising an interlocking-lug mechanism, one lug being rotated fixedly on the under-roll shaft, 75 and the other lug being carried by a gear loose on the under-roll shaft.

12. In a tobacco-stemming-machine, jaw bars; means for moving them bodily in pairs for opening and closing them; a pair of 80 stripping rolls; means for continuously rotating the rolls during the stripping operation; means for automatically separating the rolls to permit passage of a pair of co-operating jaw-bars; means for automatically closing the rolls upon an intervening tobacco leaf; and means for accelerating the speed of the rolls during each stripping rotation thereof through a portion of each rotation, whereby the tobacco stem is snapped 90 and quick ejection of stripped laminae from the rolls is obtained.

13. In a tobacco-stemming-machine, the combination of a pair of stripping rolls one having a continuously circumferentially corrugated elastic surface and the other having an elastic surface of card-clothing wires, the free ends of the wires being mounted all to point in the same direction and all to point away from the discharge sides of the 100 rolls when they are stripping, whereby the laminae may be nipped by the opposed elastic surfaces and rubbed toward the discharge side of the rolls without piercing them; a pair of jaw bars; means for moving the jaw bars rearwardly; and means for moving the working surfaces of the rolls in an opposite direction to the stem-gripping movement of the jaw bars during the stripping operation; a transversely mounted 110 wiper; and means for moving it through the path of the jaw bars.

14. In a tobacco-stripping-machine, the combination of upper and under separable stripping rolls and a stem-gripping device 115 with a slip-drive for the rolls; a positive drive for the rolls; and a mechanism for automatically throwing the positive drive into operation to accelerate the speed of the rolls during a portion of each rotation 120 thereof.

15. In a tobacco-stripping-machine, the combination of upper and under separable stripping rolls and a stem-gripping device with a slip-drive for the rolls; a positive 125 drive for the rolls and a mechanism for automatically throwing the positive drive into operation to accelerate the speed of the rolls during a portion of each rotation thereof, the rolls being mounted in slidable journal 130

boxes; means to force the rolls apart for passage of the stem-gripping devices; springs to force the rolls toward each other after passage between the rolls of the stem-gripping device; and adjustable devices to limit the inward approach of the rolls.

16. In a tobacco-stemming-machine, the combination of upper and under separable stripping members, at least one of them being rotatable with means for continuously rotating it; means for accelerating its rotation during each complete rotation; and an automatic mechanism for putting the speed accelerating means into operation as desired.

17. The combination with a stripping mechanism and a stem-gripping mechanism of a comb adjacent to and parallel with the stripping devices, and a transverse wiper operative adjacent to and across the length 20 of the comb, and means for moving said wiper past the comb for removing stripped leaf from the comb and the stripping mechanism.

In testimony whereof I affix my signature 25 in presence of two witnesses.

HENRY CONRAD HEBIG.
